UNITED STATES PATENT OFFICE.

ROBERT SCHUMANN, OF DUSSELDORF, GERMANY.

LENS-EDGING MACHINE.

Application filed March 3, 1921. Serial No. 449,279.

To all whom it may concern:

Be it known that I, ROBERT SCHUMANN, a citizen of the German Republic, and residing at Dusseldorf, Germany, have invented 5 certain new and useful Improvements in Lens-Edging Machines, of which the following is a specification.

The present invention has reference to improvements in copying lens edging machines 10 with relative axial reciprocation of the work spindle for varying the grinding zones, and it relates more particularly to improved pattern disc means in association with the work spindle, and in connection therewith to 15 means for controlling the extent of the reciprocatory displacement of the work spindle with respect to the grinding tool.

My improved edging machine permits of 20 turning out lenses of varying shapes and sizes without any interchange of machine parts, simply by shifting the circumferentially grooved contact roller to selectively 25 coact with any one of a series of pattern discs determining the shape and size of the lenses 30 to be ground. These pattern discs form a fixed part of the machine and are thus not subject to misplacement or loss. The positive control of the reciprocations of the work 35 spindle allows of a number of lenses being 40 operated on simultaneously without danger of having the respectively outermost lenses carried beyond the allotted grinding zone, when they would not be acted upon any longer by the tool and would be apt to be 45 injured on leaving and again on entering the grinding zone. This control feature also assures an even wearing down of the grinding 50 tool.

In the accompanying drawing a constructional form of the grinding machine according to the present invention is shown by 55 way of example.

Fig. 1 is a side elevation, Fig. 2 is a plan, and Fig. 3 is a front elevation of the machine. Figs. 4 and 5 are sectional views on the lines A—B and C—D, respectively. Fig. 6 is an individual part. Figs. 7 and 8 illustrate a modification of an individual part.

On the bed 1 is journalled in bearings 3 a 60 shaft 2 carrying a grinding wheel 4 and a driving pulley 90. The bed is provided with prismatic ways 5, on which is guided a slide 6, having screws 7 and plates 8 for securing said slide to its ways. On this slide 65 are provided bearings 9, in which a shaft 10 is revolvably and axially shiftably

journalled. To the shaft 10 is fixed a grooved cam-wheel 13, in which engages a pin 14, which projects shiftably through a slot 63 in a plate 15. The said plate 15 is 60 fitted to the slide 6 and carries, supported thereon by means of pins 91 a yoke 66, which is drawn downwards by means of a spring 65, whilst a set-screw 64, screwed into the top of the yoke bears on the plate 15. Thus 65 it is possible to determine the relative position between the yoke and the said plate by means of said set-screw. At the one bearing 9 is journalled a bevel-gear 47 through which the shaft 10 passes, which here carries 70 a key, by means of which the shaft is dogged when the bevel-gear revolves. The bevel-gear 47 meshes with another bevel-gear 47^a, which is attached to the one half of a clutch 52, while the other half of the clutch 52^a is 75 shiftably fitted on the shaft 59 of the bevel-gear 47^a. Into an annular groove in this clutch-member engages a forked lever 58, the shaft of which 56 is coupled to a lever 57 and turned by means of a spring 55 fitted 80 to it, in such a manner, that the clutch-member 52^a tends to engage in the clutch-member 52. To shaft 59 is fitted a worm-wheel 46, in which engages a worm 46^a, which is fitted to the shaft 2. 85

On shaft 10 is movably fitted a long sleeve 11, to which bearings 16, 24 are attached by means of brackets 12. In the bearings 16 is revolvably journalled a shaft 17, which carries at one end a plate 18 with a rubber 90 facing 19. To the shaft 17 are further fitted several pattern disc 32, the circumferential contours of which correspond to the circumferential contours of the lenses to be ground. A gear-wheel 51 fitted to shaft 17 engages 95 in another gear-wheel 50 on shaft 10. The hub of the gear-wheel 51 is held in the bore of the bearing 16 by means of a pin 91, which engages in a groove 93 in the said hub. A screw 87 in the hub of the gear-wheel 51 engages in a longitudinal groove 89 in shaft 17, so that when the said gear-wheel revolves, it will carry the shaft with it. To the outer end of shaft 17 is fitted an arm 73, in the bore of which is placed a 105 spring 84, which bears at one end against a collar 81 on shaft 17, and, at the other end, against a flange 85 of the bore. Coaxially with the shaft 17 a shaft 27 is journalled in the bearing 24, carrying a plate 25 110 with a rubber facing 26 at its one end. To this shaft is fitted a gear-wheel 71, which, by

means of a pin 92 is held in a groove 94 in the bearing 24. A screw 88 in the hub of the gear wheel engages in a longitudinal groove 90 in shaft 27, and to the outer end of the same is fitted an arm 74, in the bore of which a spring 83 is disposed, which, at one end, bears against a collar 82 on shaft 27, and, at the other end, against a flange 86 in the bore. Also this gear-wheel 71 meshes with a gear-wheel 72 on shaft 10.

From the bearings 16 and 24 are branched off arms 77 and 78, in which two shafts 75 and 76 are journaled, of which the ends turned towards each other are threaded in an opposite sense, and on the one end is screwed a threaded sleeve 80, which is held between the arms 77 and 78, and which is fitted with a small handwheel 79. The outer ends of the shafts 75 and 76 are coupled to the arms 73 and 74.

To the sleeve 11 is fitted an arm 23 carrying a weight 23^a.

On the slide 6 a shaft 36 is journaled in eyes 37, and on said shaft is fitted a rocker 35, which is forked at its upper end. In this fork a shaft 34 with a loose roller 33 is journaled. The rocker has an arm 39, which bears with a pin 38 against a nut 40 on a screw 41 in the slide 6.

To the sleeve 11 is further fitted by means of an ear 43^a a pin 43 which can engage in a notch 44 in a lever 45, which is pivoted on slide 6 and is provided with a handle 45^a.

The sleeve 11 further has a cam 62 on which the lever 57 bears.

The belt 90 will revolve the grinding wheel at a high speed and by means of the gears 46, 46^a, the shaft 59 and the wheels 47, 47^a the shaft 10 at a slow speed. The glass or the glasses to be ground are clamped between the plates 18, 25. This clamping is effected by turning the sleeve 80 and thereby moving the shafts 17, 27 apart by aid of arms 73, 74, then the glass or the glasses are inserted between them and the sleeve is turned in the opposite sense, so that the rubber pads 19, 26 clamp them. The springs 83, 84 prevent an excessive pressure being exerted, as the arms 73, 74 will shift on the shafts 17, 27 when the said springs are tightened. During the clamping of the glasses the sleeve 11 and all parts connected to it are held lifted off the grinding wheel by means of the pin engaging in the notch 44.

As soon as, now the handle 45^a is lifted, the notch 44 releases the pin 43 and the weight 23^a will pull the clamped glass against the grinding wheel, against which it, however, can only bear as far as the roller 33 will admit. The latter has previously, been shifted so that a templet-disc 32 bears against it, which corresponds in form to the shape the glass is to receive. The roller will thus hold the glass-carrier in such a position that the glass will recede from the grinding wheel

according to the shape of the templet-disc. The glass will, therefore, be ground to correspond to the said templet-disc. In order that the glass does not wear any grooves into the grinding wheel provision has been made for the glass to travel across the face of said wheel, the cam-sleeve 13 shifting the pin 14. The travel of this pin is limited by the yoke 66. As soon as, therefore, the pin abuts against the one side of the yoke, the cam-wheel 13 will, on revolving shift its position, and the shaft 10 with sleeve 11 and its parts, thus also the glass with it. By vertically displacing the yoke 66 by means of the spring 65 and the set-screw 64 the available length of the slot 63 is varied. If the available length of the slot is equal to or greater than the whole stroke of the cam-wheel, only the pin 14, and not the shaft 10 will shift. The more, therefore the yoke is lifted, the shorter will be the available length of the slot 63 and the greater will be the displacement of the shaft 10. The more glasses are ground at one time, the smaller the displacement of the shaft 10 will have to be. When the grinding operation has been completed the shafts 17, 27 with the other parts are turned off, until pin 43 engages in notch 44. Thereby the cam 62 turns the lever 57, which effects the release of the shiftable clutch-member 52.

In the modification according to Figs. 7 and 8 a lever 68 is horizontally disposed on the slide 6, and carries a pin 14. On the slide 6 is fitted a smaller slide 70, which has an angular groove 71, into which the pin 14 engages. The slide may be shifted by means of a screw 69. According to the position of the slide 70, thus also of the groove 71 to the pin 14, the lateral play of the latter will be limited. The result is, thus, the same as described above.

I claim:

1. In a lens edging machine of the character set forth, in combination with a stationary rotatable grinding tool, a support, a slide mounted on said support for reciprocation toward and away from said grinding tool, a rocking work carriage mounted on said slide, a rotatable shaft mounted in said carriage, and a differential clutch-controlled gearing connection interposed between said grinding tool and said shaft, two axially alined work spindles mounted in said carriage and driven in unison from said shaft, means for jointly reciprocating said work spindles toward and away from one another, means for reciprocating said carriage to carry said work spindles jointly in the same sense across the edge face of said grinding tool, and means for controlling the extent of such reciprocation of said carriage.

2. In a lens edging machine of the character set forth, in combination with a stationary rotatable grinding tool, work

clamping means including a driven shaft, means for imparting relative lateral reciprocation between said grinding tool and said work clamping means and means for controlling the amplitude of such reciprocation to keep it within the operative width of the grinding tool, comprising a grooved cam disc fixed on said driven shaft, a fixed bearing member presenting a transverse slot, a vertically adjustable yoke presenting a substantially triangular cut-out, and means altering the position of said yoke relative to said bearing member for controlling the operative length of said transverse slot, and a pin slidably mounted within said slot and its free end extending into the groove of said cam disc.

3. In a lens edging machine of the character set forth, in combination, a rotatable grinding tool, a relatively reciprocable and tiltable work support, including a work spindle, a series of pattern discs fixed on said work spindle, means normally holding said work spindle in operative position, means for temporarily retaining said work spindle in inoperative position, a contact roller adapted to be brought into selected cooperation with any one of said pattern discs, means for keeping said roller in operative contact with the selected pattern disc, and means for causing said contact roller to partake of the reciprocation of said work support.

4. In a lens edging machine of the

character set forth, in combination with a rotatable reciprocating work spindle, a series of pattern discs on said work spindle, a contact roller presenting a grooved circumference adapted to be selectively brought into cooperative engagement with any one of said pattern discs and to partake of the reciprocation thereof, and screw-influenced lever means for retaining said grooved roller and the selected pattern disc in operative contact.

5. In a lens edging machine of the character set forth, a work clamping instrumentality, comprising two axially aligned work spindles, means for rotating these spindles in unison, means for axially displacing said spindles in opposite directions, comprising for each spindle an arm journaling the outer end of the respective spindle and the other arm end fixed to a screw spindle extending parallel to the work spindle and presenting an outer thread, the outer threads of said two screw spindles running in opposite directions, a sleeve presenting corresponding right and left inner threads adapted for cooperation with said screw spindle threads, and means for rotating said sleeve in opposite directions; and cushioning means interposed between the outer ends of said work spindles and the respective journal ends of said arms.

In testimony whereof I affix my signature.

ROBERT SCHUMANN.
